Des. 222,230
Patented Oct. 12, 1971

222,230

ABRASIVE TYPE HAND TOOL

Robert W. Martin, 1057 Pennington Road,
Trenton, N.J. 08618

Original design application Apr. 1, 1969, Ser. No. 16,541,
now Patent No. 217,952, dated July 7, 1970. Divided
and this application Apr. 27, 1970, Ser. No. 22,659

Term of patent 14 years

Int. Cl. D8—05

U.S. Cl. D8—90

Fig. 1.

Fig. 2.

Fig. 3.

Fig. 4.

FIG. 1 is a perspective view of an abrasive type hand tool embodying my new design;

FIG. 2 is a side elevation of the abrasive type hand tool shown in FIG. 1;

FIG. 3 is an end elevation of the abrasive type hand tool shown in FIG. 1 as seen from the right hand end thereof, and;

FIG. 4 is an end elevation of the abrasive type hand tool shown in FIG. 1 as seen from the left hand end thereof.

This application is a division of applicant's copending application Ser. No. D. 16,541, filed Apr. 1, 1969, now Pat. No. D. 217,952.

I claim:

The ornamental design for an abrasive type hand tool, as shown.
